[57] CLAIM

The ornamental design for an insulated carrier for beverage cans or the like, as shown and described.

DESCRIPTION

FIG. 1 is a perspective view of an insulated carrier for beverage cans or the like showing our new design;
FIG. 2 is a front elevational view;
FIG. 3 is an end elevational view;
FIG. 4 is a top plan view; and
FIG. 5 is a bottom plan view thereof.

*Fig. 1.**Fig. 2.**Fig. 3.**Fig. 4.**Fig. 5.*
